Atty.

UNITED STATES PATENT OFFICE.

JOHN W. BATE, OF RACINE, WISCONSIN.

ADJUSTABLE STEP JACK.

Application filed June 4, 1923. Serial No. 643,243.

To all whom it may concern:

Be it known that I, JOHN W. BATE, a citizen of the United States, residing at Racine, in the county of Racine and State 5 of Wisconsin, have invented a new and useful Improvement in Adjustable Step Jacks, of which the following is a specification.

This invention relates to adjustable steps 10 for jacks and the like and is fully described in the following specification and shown in the accompanying drawings in which:

Figure 1 is a side elevation of a jack embodying the invention,

Fig. 2 is a horizontal section on the line 2—2 of Fig. 1,

Fig. 3 is a front elevation of the jack, and Fig. 4 is a vertical section on the line 4—4 of Fig. 3.

The embodiment illustrated comprises a hollow pressed sheet metal housing 10 secured to a bar 11 by means of rivets 12. A rack bar 13 is slidably mounted therein and is operated in a well known manner by 25 means of an oscillating member 14 which is pivotally mounted between the sides of the housing 10 on the rivet 15.

A shoe 16 extends around the front of the housing 10 as shown in Figs. 1 and 2 and 30 is secured at its upper end 17 to the rack bar 13 by means of reduced ends 13^a which also passes loosely through a cap 18 and is riveted over at 13^b to retain the cap thereon. A rail 19 and spacer 20 are secured to 35 the shoe 16 of the upper end by means of a rivet 21. The rail 19, spacer 20 and shoe 16 are secured at their lower ends to the lower end of the rack bar 13 by means of a rivet 22. The front of the housing 10 is 40 provided with a vertical slot 23 which permits the rivet 22 and a shouldered extension 13^c of the rack bar to pass therethrough.

A bracket 24 loosely engages the edges of the rail 19 so as to be slidable thereon. A 45 step 25 is hingedly mounted therein on a rivet 26. The lower end of this step is cut away at 25^a so as to permit it to freely swing toward and from the rail 19. The inner side of the step is provided with a lug 27 which is adapted to a series of openings 28 at the front of the rail 19, the step 50 is constantly pressed toward the rail by means of a spring 29.

It will be apparent from the foregoing

that when the lug 27 is in one of the holes 55 28 the upper end 25^b of the step may be used to lift a considerable weight such as the axle of an automobile, the weight serving to keep the lug in engagement with the hole in the rail 19, because of the position 60 of the rivet 26. If, however, the operator wishes to raise or lower the step 25 with respect to the rack bar he grasps the lower hooked end 25^c of the step and pulls it outward compressing the spring 29, at the 65 same time sliding the step up or down to the desired point when the lug 27 is again placed in one of the holes 28. The ends of the rivets 21 and 22 prevent the step and slider from being removed from the rail. 70

While I have shown and described certain embodiments of my invention, it is to be understood that it is capable of many modifications. Changes therefore in the construction and arrangement may be made 75 without departing from the spirit and scope of the invention as disclosed in the appended claims, in which it is my intention to claim all novelty inherent in my invention as broadly as possible in view of the 80 prior art.

I claim:

1. In a jack, a vertically movable lifting member, a track secured thereto forming a lifting unit, said unit having a series 85 of notches therein, a bracket slidably mounted on said track, a step hingedly mounted on said bracket, a lug on said step, and means for yieldingly holding said lug in engagement with said notches. 90

2. In a jack, a vertically movable lifting member, a track carried by said member, said track having a series of notches therein, a bracket slidably mounted on said track, a step hingedly mounted on said bracket, a lug on said step, and a spring holding said 95 lug in engagement with said notches.

3. In a jack, a housing, a vertically movable lifting member slidable therein, a track outside said housing and secured to said member, said track having a series of notches therein, a bracket slidably mounted on said track, a step hingedly mounted on said bracket, a lug on said step, and means 100 for yieldingly holding said lug in engagement with said notches. 105

JOHN W. BATE.
